PACKAGED MATERIAL AND DEVICE

Philip N. Hills, Norwood, and Harry N. Mann,
Walpole, Mass., assignors to Bird & Son, Inc.,
East Walpole, Mass., a corporation of Massa-
chusetts

Application April 5, 1933, Serial No. 664,482

12 Claims. (Cl. 206—59)

This invention relates to packaged material and a device therefor, and has particularly to do with the provision of a novel form of packaged rolled sheet material such, for example, as felt base rugs, 5 linoleum or the like, though the invention is also useful for packaged tape, wire, shoe welting and other products.

Heretofore, it has frequently happened that rolled material has been injured due to rough 10 handling during transportation and it is the object of this invention to provide an improved package whereby such injury will be avoided and the rolled material protected from damage due to dropping or other contact with objects usually 15 encountered in the shipment and handling of such material.

In the drawings, which show the preferred forms of package there is shown rolled sheet material such as a rug or the like;

Fig. 1 is a perspective view of the complete package;

Fig. 2 is a perspective view showing one of the end plugs or protective devices;

Fig. 3 is a sectional view, partly in elevation, 25 showing in detail the assembly of the protective device, rolled sheet material, and wrapping for said material;

Figs. 4—8 inclusive, illustrate a modified form of package in which Fig. 4 is a perspective view 30 showing an end plug or protective device;

Fig. 5 is a perspective view of one end of the tube ready to receive the protective device of Fig. 4;

Fig. 6 is a perspective view showing a roll of sheet material and the application of plugged tubes thereto;

Fig. 7 shows the roll of Fig. 6 after the plugged tubes have been brought in abutting contact and sealed with an encircling band of adhesive tape, 40 and;

Fig. 8 is a longitudinal cross section, partly in perspective, illustrating more in detail one end of the package.

Referring to the drawings.—

In the package as shown in Figs. 1—3, a tube 2 has rolled thereabout a rug 4 or the like, and at the ends thereof are positioned end protective devices generally designated at 6. These devices include a ring or series of annular rings 8 of fiber or other suitable material. On the outside of the device 6 is an annular ring 9 and on the inside of the annular rings 8 is a ring or series of rings 10 which in turn have adjacent thereto, a series of smaller rings 11, the latter being within the tube 2. The rings 10 and 11 may be made of fiber or

other suitable material though in the device as shown there is employed corrugated board of the usual type used for box making purposes. The annular rings 8, 9, 10 and 11 are held together by means of the tube 12 flanged over at its ends 14, though the said rings may be otherwise attached together for example, by wires, nails or bolts passing therethrough, or by adhesive attachment. If such fastening means is employed, if desired, discs may be substituted for the annular rings 8, 9, 10 and 11. In Fig. 3 the tube 2 is shown as extending beyond the end of the rolled sheet material 4 so as to provide a space 16 and there is then preferably passed thereabout, a wrapping 17 of paper or other sheet or web material encircled at its ends 18 by the gummed tape 18 which serves to hold in place the wrapping 17. It will be noted that the external diameters of the rolled material 4, wrapping 17, and gummed tape 18, are somewhat smaller than the external diameter of the annular rings 8 which thus provide a protective shoulder and save the gummed tape 18 from wear and tear during handling.

Though not apparent from the drawings, the annular rings 11 shoulder preferably be of such diameter as to require some pressure (hand pressure is ample) to force the device into the tube 2 (if a tube be employed) which causes the rings or discs to be a bit cupped or otherwise distorted so that by friction they lock themselves to the inner wall of the tube or roll in such a way as to make the device difficult of removal from the roll. Though in the device as shown a tube 2 is employed, it is not necessary for the packaging of all materials, for, even though a tube be employed in the winding of the sheet material, it may then be removed prior to the insertion of the protective device. In this case, however, it will be obvious that the size of the annular rings 11 will have to contact the inner diameter of the roll of sheet material rather than the inner diameter of the tube as shown in Fig. 3. For efficient and uniform packaging of tape, wire, shoe welting and the like, the tube, or equivalent, is, of course, essential. It will be evident from the above that there is provided a package which is adequately protected at the ends thereof regardless of the angle at which the package may be dropped, pushed or pulled along other surfaces. The shoulders provided by the ends 8 serve to minimize the wear and tear through the intermediate portion of the roll and the rings at the end, especially if they be corrugated, act as a cushion and shock absorber when the package is dropped against the end of the hollow core and against the end of the web wound on

said core. The enclosed air chamber or space [16], if employed, also assists in protecting the wrapped material from injury.

In the remaining figures of the drawings (Figs. 5 4-8 inclusive), there is shown a package of somewhat wider application which may be used as a container for almost any sort of merchandise which it is desired to pack, store or ship. The package of these figures likewise includes an end 10 plug or protective device made up of a series of flat members such as discs 20, or annular rings 21, which are assembled and secured together in any suitable manner in axial alignment. Here, as in the case of the rings or discs 11, the diameter is such as to require some pressure to force the device into an end of the tube 22 (as in Fig. 15 5) and thus to cause the rings or discs to be a bit cupped or distorted so that by friction they lock themselves to the inner wall of the tube and 20 strongly resist. Once in place, the plug is not readily removable from the tube except by a continuation of the movement in the entering direction.

In Fig. 6 is shown a roll of sheet material 24, such as a felt base rug and two sections of tube 22, each having an outside end plugged. The two tubes, thus plugged, are of such a length as to receive the plugs or protective devices in the ends thereof, completely enclose the rug 24, and still 25 be brought into end to end or abutting contact 30 as shown in Fig. 7, after which there may be applied, encircling the joint, an adhesive strip 26 which serves to seal the joint and fasten together the two tubular sections 22. In this way the package 35 is completed and the rug or the like completely enclosed and protected ready for shipment. If the annular ring type of plug be employed and it is desired to make the package dust tight, or 40 to provide an end seal for either type of plug, an adhesive sticker or strip may be applied across the end of the plug and extending down the sides of the tube,—thus to seal the joint between the plug and the tube and indicate if the package has 45 been opened or tampered with. It will be appreciated that a single tube may be utilized in which but one of the end protective devices of this invention be employed, the other end being closed by any suitable means.

In Fig. 8 there is shown a cross sectional view 50 illustrating the rug in position in the tube with one of the protective devices in place. In the package as shown, there is no necessity for an internal tube and accordingly none is shown. The external tube 22 provides sufficient longitudinal 55 rigidity and at the same time affords a degree of protection not provided by the paper wrapping 17 of the earlier group of figures.

Having described our invention, what we wish to claim and secure by Letters Patent is:

60 1. A roll of sheet material in transportable form consisting of a tube having rolled thereon the said sheet material, said tube having at the opposite ends thereof, protective devices comprising a series of round, flat members frictionally engaging and plugging internally the ends of said tube and also having beyond the ends of said tube, a series of members of larger diameter and substantially equal to the external diameter of said rolled sheet material, a wrapping for said sheet material supported thereby, extending beyond the ends thereof and attached to the larger diameter of said protective device.

65 2. A roll of sheet material in transportable form consisting of a tube having rolled thereon the said sheet material, said tube having at the opposite

ends thereof, protective devices comprising a series of round, flat members frictionally engaging and plugging and closely fitting the internal diameter of said tube and also having beyond the ends of said tube, a series of members of larger diameter and substantially equal to the external diameter of said rolled sheet material, a wrapping for said sheet material supported thereby, extending beyond the ends thereof and attached beyond the ends of said tube to the larger diameter of said protective device. 10

3. A roll of sheet material in transportable form consisting of a tube having rolled thereon the said sheet material, said tube having at the opposite ends thereof, protective devices comprising a series of round flat members and plugging internally the ends of said tube, said devices presenting to the bore of said tube angular circumferential edges of said members adapted to frictionally engage the said bore and also having beyond the ends of said tube, a series of members of larger diameter and substantially equal to the external diameter of said rolled sheet material, the said sheet material being surrounded by a wrapping extending beyond the ends thereof and attached beyond the ends of said tube to the larger diameter of said protective device. 15

4. A roll of sheet material in transportable form consisting of a tube having rolled thereon the said sheet material, said tube having at the opposite ends thereof, protective devices comprising a series of round flat members, said members being attached by a hollow, flanged tube extending therethrough and plugging internally the ends of said tube and also having beyond the ends of said tube, a series of members of larger diameter and substantially equal to the external diameter of said rolled sheet material, the said sheet material being surrounded by a wrapping extending beyond the ends thereof and attached beyond the ends of said tube to the larger diameter of said protective device. 20

5. A roll of sheet material in transportable form having a longitudinal tubular member associated therewith, said tubular member having at the opposite ends thereof protective devices plugging internally the ends of said tube and maintaining the sheet material therebetween, each of said devices including a series of round flat members axially aligned and attached together, said devices presenting to the internal surface of said tubular member a series of circumferential edges of said members, adapted to frictionally engage the said internal surface. 25

6. A roll of sheet material in transportable form 30 having a longitudinal tubular member associated therewith, said tubular member having at the opposite ends thereof devices maintaining the sheet material therebetween, at least one of said devices including a series of round flat members axially aligned and attached together and presenting to the internal surface of said tubular member circumferential edges adapted to frictionally engage the bore of said member. 35

7. A roll of sheet material in transportable form having a two-part longitudinal tubular member associated therewith, said tubular member having at the opposite ends thereof protective devices plugging internally the ends of said tube and maintaining the sheet material therebetween, each of said devices including a series of round flat members axially aligned and attached together, said devices presenting to the internal surface of said tubular member a series 40

of circumferential edges of said members, adapted to frictionally engage the said internal surface.

8. A shipping container for merchandise comprising a longitudinal tubular member, closure devices for the ends of said tubular member, at least one of said devices comprising a series of flat members axially aligned and attached together and presenting to the bore of said tubular member, angular peripheral edges of said series members, adapted to frictionally engage the said bore.

9. A shipping container for merchandise comprising a longitudinal tubular member, closure devices for the ends of said tubular member, at least one of said devices comprising a series of flat corrugated board members axially aligned and attached together and presenting to the bore of said tubular member angular edges of said series members adapted to frictionally engage the said bore.

10. A shipping container for merchandise comprising a longitudinal tubular member, closure devices for the ends of said tubular member, each of said devices comprising a series of relatively thin members axially aligned and attached to-

gether and presenting to the bore of said tubular member corners of said series members adapted to frictionally engage the said bore.

11. A roll of sheet material in transportable form having a longitudinal tubular member associated therewith, said tubular member having at the opposite ends thereof devices plugging internally the ends of said tube and maintaining the sheet material therebetween, at least one of said devices including a series of relatively thin round members axially aligned and attached together and distorted to vary the diameter thereof, so as to frictionally engage the bore of said tubular member.

12. An imperforate container for merchandise comprising a longitudinal tubular member, closure devices for the ends of said tubular member, at least one of said devices including a series of relatively thin, semi-flexible members axially aligned, attached together and distorted to vary the diameter thereof, so as to frictionally engage the bore of said tubular member.
